US00D926260S

(12) **United States Design Patent** (10) **Patent No.:** **US D926,260 S**
(45) **Date of Patent:** **** Jul. 27, 2021**

(54) **GAMING MACHINE**

- (71) Applicant: **AGS LLC**, Las Vegas, NV (US)
(72) Inventors: **Mark Steven Ross**, Las Vegas, NV (US); **Kevin Lee Hohman**, North Las Vegas, NV (US)
(73) Assignee: **AGS LLC**, Las Vegas, NV (US)
(**) Term: **15 Years**
(21) Appl. No.: **29/696,810**
(22) Filed: **Jul. 1, 2019**

Related U.S. Application Data

- (63) Continuation of application No. 29/627,931, filed on Nov. 30, 2017, now Pat. No. Des. 852,890.

CLAIM

The ornamental design for a gaming machine, as shown and described.

DESCRIPTION

FIG. 1 is a front isometric view of the gaming machine of the present invention;

FIG. 2 is a top plan view of the gaming machine illustrated in FIG. 1;

FIG. 3 is a front elevation view of the gaming machine illustrated in FIG. 1;

FIG. 4 is a first side view of the gaming machine illustrated in FIG. 1;

FIG. 5 is a second side view of the gaming machine illustrated in FIG. 1;

FIG. 6 is rear elevation view of the gaming machine illustrated in FIG. 1; and,

FIG. 7 is a bottom plan view of the gaming machine illustrated in FIG. 1.

The broken lines in the drawings are for the purposes of illustrating portions of the gaming machine which form no part of the claimed design.
